US0D1065113S

(12) **United States Design Patent** (10) Patent No.: **US D1,065,113 S**
(45) Date of Patent: ** Mar. 4, 2025

(54) **SWITCH**

(71) Applicant: **Shenzhen Sunricher Technology Co., Ltd.**, Shenzhen (CN)

(72) Inventor: **Fei Gong**, Shenzhen (CN)

(73) Assignee: **Shenzhen Sunricher Technology Co., Ltd.**, Shenzhen (CN)

(**) Term: **15 Years**

(21) Appl. No.: **29/880,582**

(22) Filed: **Jul. 25, 2023**

(30) **Foreign Application Priority Data**

May 8, 2023 (CN) 202330263154.X

(51) **LOC (15) Cl.** **13-03**
(52) **U.S. Cl.**

USPC **D13/158**; D13/169; D13/171

(58) **Field of Classification Search**

USPC D13/169, 171, 170, 162, 164, 184, 199,
D13/182, 158, 173, 174, 177, 168
